INDIRECT LIGHTING FIXTURE

Charles D. Poey, Bayside, N. Y., assignor to The Miller Company, Meriden, Conn., a corporation of Connecticut

Application August 31, 1937, Serial No. 161,741

4 Claims. (Cl. 240—78)

The present invention relates to indirect lighting adapted to use a mercury vapor light source and a plurality of incandescent lamp bulbs.

The present invention contemplates a fixture 5 of the type referred to wherein the transformer for supplying the mercury vapor lamp is mounted in the fixture underneath a reflecting plate, which acts on light from all the lamps to reflect it upwardly. The incandescent lamp bulbs are 10 preferably carried in sockets supported below this plate, and the entire assembly is surrounded by an ornamental cover and a light reflector for producing indirect lighting.

Other objects and advantages will hereinafter 15 appear.

The accompanying drawing shows, for purposes of illustrating the present invention, a selected embodiment in which the invention may take form, it being understood that the drawing is 20 illustrative of the invention rather than limiting the same.

In the drawing:

Figure 1 is a vertical sectional view of a pendant lighting fixture with parts in section; 25 Figure 2 is a top plan view with parts broken away to show interior construction;

Figure 3 is a wiring diagram; and

Figure 4 is an outline view illustrating a lamp or torchère type of fixture embodying the present 30 invention.

The suspension for the pendant type fixture is indicated at 10. It is provided with four downwardly extending tubular arms 11. These arms are threaded at the lower end to receive nuts 12. 35 They pass through a reflecting plate 13 and the plate 14, which supports a transformer indicated at 15. The lower ends of the arms 11 also pass through bracket straps 16, and the assembly is clamped together by nuts 17 threaded on to the 40 lower end of arms 11.

The straps 16 support upwardly opening lamp sockets 18, and these carry incandescent lamp bulbs 19, the necks of the bulbs passing down through apertures 20 in the plate 13. As indicated in the drawing it is possible to support various size lamp bulbs from the lamp sockets. 45

The plate 13 also carries an upwardly extending strap or bracket 21 adapted to support a horizontal lamp socket 22. This socket carries a 50 mercury vapor lamp bulb 23. The lower end of the transformer 15 is provided with the usual crowfoot 24, which supports a dependent stem 25. This stem by means of an ornamental knob 26 supports a transformer cover 27. This cover 55 27 fits against three straps or arms 28 carried by

a plate 29. The arms 28 support a louver ring, indicated at 30, and an upwardly and outwardly flaring reflector 31. The upper ends of the arms or straps 28 fit the periphery 32 of the plate 13, so as to hold the parts in alignment. 5

The fixture wires 33 and 34 are carried down through the tubular arms 11 and are connected through a switch 35 with the incandescent lamps 19. They are also connected through a switch indicated at 36 to the transformer 15, which in 10 turn is connected to the mercury vapor lamp 23.

Where the organization is to be used as a floor torchère, the upper suspension is omitted, and the entire structure suitably supported from a pedestal or post, such as indicated at 40 in Figure 4. 15

It will be apparent from the foregoing that one could operate either or both light sources, and that in either case a well directed flood of light is directed toward the ceiling. The lamp bulbs are all effectively concealed by the reflector 20 31. When the incandescent lamp bulbs are operated, sufficient light escapes from the necks of the bulbs and scatters around underneath the plate 13 to bring about an illumination of the lower surfaces of the reflector 31 and the louver 25 30, this light escaping through the spaces below these elements.

It is apparent that, within the scope of the invention, modifications and different arrangements may be made other than is herein disclosed, 30 and the present disclosure is illustrative merely, the invention comprehending all variations thereof.

What is claimed is:

1. An indirect lighting fixture comprising a 35 substantially horizontal reflecting plate having peripherally arranged bulb receiving openings, a horizontal lamp socket above the plate, a mercury vapor lamp bulb carried in the socket and disposed above the plate, a centrally disposed 40 transformer secured below the plate and wired to the said lamp socket, a plurality of upwardly opening lamp sockets supported outside the transformer and a substantial distance below the openings in the plate, incandescent lamp bulbs in 45 the upwardly opening sockets, the necks of the incandescent lamp bulbs being below the plate, and an outwardly and upwardly flaring reflector beyond the edge of the plate to screen all the bulbs and reflect light upwardly. 50

2. An indirect lighting fixture comprising a substantially horizontal reflecting plate having peripherally arranged bulb receiving openings, a horizontal lamp socket above the plate, a mercury vapor lamp bulb carried in the socket and 55

- disposed above the plate, a centrally disposed transformer secured below the plate and wired to the said lamp socket, a downwardly extending stem below the transformer, a plurality of upwardly opening lamp sockets supported outside the transformer and a substantial distance below the openings in the plate, incandescent lamp bulbs in the upwardly opening sockets, the necks of the incandescent lamp bulbs being below the plate, an outwardly and upwardly flaring reflector beyond the edge of the plate to screen all the bulbs and reflect light upwardly, and means for supporting the flaring reflector from the stem.
3. An indirect lighting fixture comprising a substantially horizontal reflecting plate, a horizontal lamp socket, a mercury vapor lamp bulb carried in the socket, and disposed above the plate, a centrally disposed transformer secured below the plate and wired to the said lamp

socket, a plurality of upwardly opening lamp sockets supported below the plate and outside the transformer, incandescent lamp bulbs in the upwardly opening sockets, the outer portions of the plate being apertured to accommodate the incandescent lamp bulbs, an outwardly and upwardly flaring reflector beyond the edge of the plate to screen all the bulbs and reflect light upwardly, downwardly and inwardly extending straps secured to the flaring reflector and fitted to the periphery of the horizontal plate, and means for supporting the lower ends of the straps from the bottom of the transformer.

4. A lighting fixture such as claimed in claim 3, having an annular transformer concealing louvre secured to the straps, its upper edge being spaced from the lower edge of the reflector to reflect light from the neck of the lamp bulb on to the outer surface of the flaring reflector.

CHARLES D. POEY. 20
